HEAT EXCHANGE APPARATUS

Robert A. Bowman, Folcroft, Pa., assignor to
Westinghouse Electric & Manufacturing Com-
pany, East Pittsburgh, Pa., a corporation of
Pennsylvania

Application November 22, 1940, Serial No. 366,584

1 Claim. (Cl. 257—28)

This invention relates to heat exchange apparatus, more particularly to heat exchangers containing a desuperheating section, and has for an object the provision of improved apparatus of this character.

Another object of the invention is the provision of heat exchange apparatus having a desuperheating section comprised by a plurality of vertically-extending inverted U-tubes, together with means between the legs of the U-tubes for separating the space surrounding said tubes into a desuperheating first section and a condensing second section, the length of said U-tubes being selected so as to assure that the line between desuperheating and condensing occurs in the second condensing pass past the bend in the U-tubes.

Yet another object of the invention is the provision of heat exchange apparatus having a desuperheating section and including a plurality of inverted U-tubes with a group of the tubes of lesser length than the remaining tubes and a portion of the shorter tubes constituting a desuperheating section.

These and other objects are effected by the invention as will be apparent from the following description and claim taken in connection with the accompanying drawing, forming a part of this application, in which:

Fig. 1 is a vertical sectional view taken along the line I—I of Fig. 3 looking in the direction of the arrows and showing apparatus constructed in accordance with the present invention;

Fig. 2 is a view similar to Fig. 1 but taken along the line II—II of Fig. 3 looking in the direction of the arrows; and

Fig. 3 is a transverse sectional view taken along the line III—III of Fig. 1 looking in the direction of the arrows.

Referring to the drawing more in detail, there is shown heat exchange apparatus of the vertical type comprising a shell 9 having an exhaust steam inlet connection 10 and housing a plurality of longitudinally-extending, inverted U-tubes having their terminal portions extending through and supported by the tube plate 12. Preferably, this tube plate is a portion of the waterbox structure 13, which is provided with a water inlet 14 and a water outlet 15, which, together with the partitions 16 and 17 therein, provide for circulation of water through the tubes in a plurality of passes, in this case four passes. The waterbox may be provided with openings 18 in alignment with the terminal portions of the tubes 11,

5 the openings being closed by conventional means such as the covers 19, held in place by the bolts 20 and bolting rings 21. The upper end of the shell is closed in any suitable manner, as by the cover 23 welded thereto, as at 24.

A baffle 26 extends longitudinally of the shell from wall to wall thereof and separates a group 27 of the tubes 11 from the remaining tubes, at 28. Preferably, the baffle 26 is sealed with respect to the shell at its vertical edges by suitable means, such as the Lamiflex seals 29, described in United States Patent Nos. 1,803,034 and 1,803,-035.

10 A similar but shorter baffle 31 extends vertically between the legs of the U-tubes of the separated group 27 and divides the space within the shell surrounding this group into a desuperheating first steam pass A and a condensing second steam pass B. The lower end of the desuperheating pass A is in communication with the steam inlet 10, while the second steam pass B has at its lower end an opening 32 through the baffle 26 whereby steam entering the apparatus through the inlet 10 passes upwardly through the desuperheating first steam pass, over the top of the baffle 31, downwardly along the second steam pass B and through the opening 32 into the final condensing steam pass C.

15 Condensate collecting in the steam passages B and C leaves the apparatus through the condensate outlet 34, while air and non-condensable gases are led off from the top of the shell through the air offtake 35, positioned above the final steam pass C. Preferably, the baffle 31 separating first and second steam passes, A and B, respectively, is provided with suitable sealing means between its vertical edges and the shell, such as the Lamiflex seals 36.

20 The tubes of the separated group 27 are shorter than those of the remaining group 28 to insure that desuperheating will occur throughout the length of the first steam pass A with the transition point from desuperheating to condensing occurring past the bends in the tubes of the group 27 considered in the direction of steam flow, whereby it is assured that no condensate will collect on any portion of the tubes of this group where it could flow down onto the desuperheating surface.

25 Inasmuch as this transition point between desuperheating and condensing may vary in location with changes in operating conditions, it may be desirable that the tubes be of such length that the transition point, under normal

operating conditions, will occur about midway of the second steam pass B. This provides, in effect, a factor of safety, whereby upon change in operating conditions there is still suitable length of condensing surface available in the second pass to take care of shifting of the transition point relative to the high point in the bend of the U-tubes.

In order to prevent steam which may pass over the top of the longitudinally-extending baffle 26 from condensing at the other side thereof and the condensate collecting upon the tubes of the desuperheating section, there is provided a transversely-extending baffle 38 overlying the tubes of the first two steam passes and sealed with respect to the shell, as at 39. An opening 40 is provided through the baffle 26 just above the transverse baffle 38 to provide for flow of condensate collecting upon the latter to the condensing section C and thence to the condensate outlet 34.

While the invention has been shown in but one form, it will be obvious to those skilled in the art that it is not so limited, but is susceptible of various changes and modifications without departing from the spirit thereof, and it is de-

sired, therefore, that only such limitations shall be placed thereupon as are specifically set forth in the appended claim.

What is claimed is:

5 Heat exchange apparatus comprising a vertically-disposed shell, a plurality of inverted U-tubes extending vertically in said shell, water-box structure associated with the terminal portions of said tubes and providing for circulation of water therethrough in a plurality of passes, a first vertical baffle separating a group of the U-tubes from the remainder thereof, a second vertical baffle disposed between the legs of the U-tubes of said separated group and dividing the space surrounding the latter within the shell into first and second steam passes, said shell having a steam inlet to the lower end of the first steam pass and a condensate outlet from the lower end of the last steam pass, and the U-tubes of said separated group being shorter than the remaining tubes and of such length that the transition point from desuperheating to condensing occurs in the second steam pass beyond the bend in the tubes considered in the direction of steam flow.

20 ROBERT A. BOWMAN.
